UNITED STATES PATENT OFFICE.

WILLARD A. CLARKE, OF STILLWATER, MINNESOTA, ASSIGNOR TO THE NORTH WESTERN MANUFACTURING AND CAR COMPANY.

TRACTION-ENGINE.

SPECIFICATION forming part of Letters Patent No. 286,906, dated October 16, 1883.

Application filed March 6, 1883. (No model.)

To all whom it may concern:

Be it known that I, WILLARD A. CLARKE, a citizen of the United States, residing at Stillwater, in the county of Washington and State 5 of Minnesota, have invented certain new and useful Improvements in Traction - Engines, of which the following is a specification, reference being had therein to the accompanying drawings.

10 Figure 1 is a top plan view of a portion of a traction-engine large enough to illustrate the method of applying thereto my improvements. Fig. 2 is a sectional view on line $x-x$, Fig. 1. Fig. 3 is a sectional view on line $y-y$, Fig. 1. Fig. 4 is a sectional view on line $z-z$, Fig. 1. Fig. 5 is an elevation of the devices shown in Fig. 1. Fig. 6 is a sectional view on line $v-v$, Fig. 1.

15 In the drawings, A represents the boiler, which, together with the engine proper, the ground-wheels, and the parts incident thereto, may be of any ordinary or preferred construction.

20 B represents the main engine-shaft, which is ordinarily in my construction placed across the end of the boiler and above the same. Upon the side of the engine where power is applied to the shaft, it may be mounted in any preferred bearings. On the side where it is 25 connected with the driven parts it is mounted, preferably, in a bearing of the character to be described, and which is indicated, generally, by the letter B'. This bearing is provided with a bracket, C, which is bolted to the side of the 30 boiler. This is cast with the curved plate c, one or more vertical webs, c' c', a lateral web, c'', and a semicircular web or flange, c''. c' is 35 the cap-piece for the box-or bearing, it being also cast with a flange or semicircular web, 40 c'', which, when the cap c' is in proper place around the shaft, coincides with the part c''.

45 The power is transmitted from the main shaft B to the traction devices by means of a friction-clutch, one part of which is carried by the shaft and the other of which is mounted loosely around the shaft, said loosely-mounted part being connected with the traction devices by a chain, D, engaging with sprocket-teeth d, or in any other preferred way. The 50 parts of the clutch are represented by E and F, the part F being keyed or otherwise se-

cured to the shaft, and the part E being loose thereon. The periphery of the part F is of the form of a frustum of a cone, and with the external surface thereof the interior surface of 55 the part E can engage when the latter is thrust against it longitudinally of the shaft. This thrust of the part E is effected by means of a forked lever, G, the ends of which have a loose connection with the part E by means of a loose 60 collar, g, and loops g' g', carried thereby and fitting the ends of the forked lever G. To receive the loose collar g, the part E of the clutch is formed with an elongated hub, E', which has a groove or channel to receive the loose 65 collar g, there being a flange at e, against which said ring can abut when it is desired to move the clutch-piece E away from the part P. It will be seen that the ring g, being loose relatively to the part E, it (said ring) will be stationary while the part E and its hub E' are 70 revolving. The forked lever G is pivoted at g' to a supporting-arm, g'', the latter having a base-plate, g''', which is bolted to the web c'', cast with the bracket, and also plates g'' g'', be- 75 tween which is situated the arm G' of the lever, the plates operating to brace and strengthen it. At the inner end the lever is pivotally connected to a forked bar, H, one leg or prong of the fork lying above and the other below the 80 shaft B, they being situated transversely across the shaft.

I is a threaded rod, one end of which engages with a nut, i, on the forked bar H, the other end of it engaging with a nut at i', carried 85 by a bracket, I'. This rod I is provided with a crank or hand-wheel, i'', by which it can be readily rotated, and when the rod I is rotated in one direction, it will be seen that the shifting-lever G will be turned upon its pivot, and 90 the part E of the clutch will be thrust into engagement with the part F, and when said rod I is rotated in the other direction, the parts of the clutch will be separated. I have shown the threads on the rod I as being in opposite 95 directions, and when they are so arranged the clutch can be moved to and fro rapidly. By means of a screw for causing the engagement and disengagement of the clutch, I can force the friction faces thereof into a strong contact and 100 hold them together with great rigidity.

By employing a forked bar, like that at H,

for connecting the screw-rod with the ship-
ping-lever, I can apply the connecting and dis-
connecting power to great advantage, it affect-
ing the sliding parts uniformly on all sides.
5 The screw-rod, it will be seen, moves the bar
H longitudinally, and therefore greater free-
dom and play is allowed the bar than if it be
positively connected to some stationary part
10 of the engine, as has been customary hereto-
fore when screw-shafts have been used for this
purpose, the part with which the screw-shaft
engages having, in prior machines, been ar-
ranged to rock about a fixed pivot.
- Machines of this class are used, not only for
15 traction purposes, but also largely as motors,
being employed for the driving of thrashing-
machines, separators, &c. It is well known to
those practically experienced with them that
20 when the engine is being used for such pur-
poses as those last above mentioned there has
been much impairing and destroying of the
engine-shafts, as those engines have been here-
tofore constructed, from the fact that when the
25 clutch-faces are not engaged the stationary
part rests in frictional contact with the shaft,
the latter revolving rapidly inside of it. To
avoid the cutting and destroying of the shafts
from this cause, I have devised and shown a
30 form of support for the sliding part of the
clutch, which I have found to be of a superior
character.

K represents a sleeve which is placed loosely
around the shaft B, and which is cast with a
35 flange, k, which latter is adapted to lie against
and to be firmly bolted to the parts c^3 c^5 , above
described, said parts c^3 c^5 being stationary and
held rigidly firm by the bracket C. Around
this sleeve K is fitted the sliding part E of the
40 clutch and its hub F.
40 It will be seen that when thus supported
upon the bracket independently of the shaft,
the sliding part of the clutch will not at any
time rest in direct frictional contact with the
shaft, and therefore there can be no serious
45 cutting or impairing of the shaft by it when
it is stationary and the shaft is rotated, as it
is when the engine is being used as a motor
for thrashing or other purposes.

What I claim is—
50 1. In a traction-engine, the combination,
with the main engine-shaft, of a friction-clutch
one member of which is adapted to be held sta-

tionary relatively to the shaft, the bracket C,
secured to the boiler and carrying one of the
bearings for the shaft, and the clutch-support 55
secured to said bearing-bracket and arranged
to support independently of the shaft that part
of the clutch which can be held stationary, sub-
stantially as set forth.

2. The combination of the main engine-shaft, 60
the friction-clutch thereon, one member of
which can slide, the bracket secured to the
boiler, which provides a bearing for the shaft,
a stationary sleeve secured to said bearing-
bracket and adapted to loosely support the 65
sliding part of the clutch, substantially as set
forth.

3. The combination of the main engine-shaft,
the friction-clutch thereon, of which clutch one
member slides, the bearing-bracket secured to
the boiler, which provides a bearing for the
70 shaft, the flange or plate c^3 c^5 , rigidly secured
to said bracket, the stationary sleeve K, which
provides a loose mounting for the sliding part
of the clutch, and the flange k, rigidly secured
75 to said sleeve and to the parts c^3 c^5 , substan-
tially as set forth.

4. The combination of the main engine-shaft,
the friction-clutch, of which one member slides,
the means for moving said member, and the 80
threaded rod having two threaded engage-
ments, the two threads being of opposite in-
clination, substantially as set forth.

5. The combination of the main shaft, the
friction-clutch, of which one member slides, 85
the means for moving said sliding member,
and the forked bar situated partly above and
partly below the engine-shaft, substantially as
set forth.

6. The combination of the friction-clutch 90
having a sliding member, a shifting-lever en-
gaging with the sliding member of the clutch,
a screw-rod for operating said lever, and a bar
or link interposed between the rod and shift-
ing-lever, it being supported entirely on said
95 screw-rod and lever, and arranged, substan-
tially as set forth, to be moved longitudinally
by the screw-rod.

In testimony whereof I affix my signature in
presence of two witnesses.

WILLARD A. CLARKE.
